UNITED STATES PATENT OFFICE.

FRIEDERICK MUELLER, OF NEWARK, NEW JERSEY, ASSIGNOR TO THE SINGER MANUFACTURING COMPANY, A CORPORATION OF NEW JERSEY.

EMBROIDERING-MACHINE.

SPECIFICATION forming part of Letters Patent No. 735,559, dated August 4, 1903.

Application filed January 13, 1903. Serial No. 138,875. (No model.)

To all whom it may concern:

Be it known that I, FRIEDERICK MUELLER, a citizen of the United States, residing at Newark, in the county of Essex and State of New Jersey, have invented certain new and useful Improvements in Embroidering - Machines, of which the following is a specification, reference being had therein to the accompanying drawings.

This invention relates to a machine for fancy stitching and embroidering, and has for its object to provide a machine of comparatively simple construction by which a large variety of ornamental or embroidering seams may be produced merely by simple adjustments and without change of parts and which admits of a great increase in the number of ornamental or embroidering seams by the use of interchangeable cams.

The improved machine in its preferred form comprises a needle-bar provided with two needles mounted to reciprocate vertically in a horizontally - swinging needle - bar frame or gate to which is imparted a step-by-step movement across the line of the feed of the work for several successive stitches in each direction alternately, and coöperating with the two needles and their loop-taking device or devices is a horizontally - swinging thread-carrier which interweaves an embroidering - thread back and forth into the ornamental seam and crosswise of the stitches formed by the needles and loop-taker. The step-by-step horizontal movements of the needle-bar and needles are produced and controlled by an intermittently - rotating cam connected with the swinging needle-bar frame or gate and operated from a continuously - rotating cam - wheel geared to the main shaft of the machine and actuating an arm or lever connected by a pitman to a clutch device which imparts the proper movements to the said intermittently - rotating cam. The horizontally - swinging embroidering - thread carrier is preferably actuated from a peripheral cam - groove in the said continuously - rotating cam - wheel.

In the accompanying drawings, Figure 1 is a front side view of the improved machine with the work-plate in section. Fig. 2 is a plan view of the same with part of the arm broken out. Fig. 3 is a front end view of the

machine with the face-plate removed. Fig. 4 is a detail view, partly in horizontal section, to show the mechanism for operating the embroidery-thread carrier. Figs. 5 and 6 are detailed views of different forms of intermittently - rotating cams for moving the needle-bar frame or gate laterally. Fig. 7 is an edge view of the continuously - rotating cam - wheel, showing the cam - groove from which the thread - carrier is operated. Figs. 8, 9, 10, and 11 illustrate different forms of seams made by the machine.

Referring to the drawings, 12 denotes the bracket-arm, and 13 the work-plate, of the machine. Mounted in the upper part of the arm 12 is the main shaft 14, provided at its forward end with a crank 15, connected by a pitman 16 with the needle-bar 17, carrying the needles 18 and reciprocating vertically in a horizontally - swinging frame or gate 19, pivoted vertically on center screws 20. The shaft 14 is provided with a bevel-gear 21, meshing with a larger bevel-gear 22, rotating at half the speed of the driving bevel-gear 21, fixed to said shaft. Rigidly connected to or integral with the gear 22 is a cam - wheel 23, having in its front face a cam - groove 24, entered by a pin or roller - stud 25 on a swinging arm or lever 26, fulcrumed at 27 by a rocking shaft or stud suitably journaled in the bracket-arm 12. The shaft 14 carries a second bevel-gear 28, meshing with a similar bevel-gear 29 at the upper end of a vertical shaft 30, having at its lower end a crank 31, connected by a pitman 32 to a rocker, from which is operated the oscillating shuttle 33, coöperating with the two needles 18. The mechanism thus far described, as also the feeding mechanism operated from the vertical shaft 30, has long been in use and is familiar to those skilled in the art.

Suitably supported from the bracket-arm 12 is a cam - wheel 34, to which an intermittently - rotating movement is imparted from the swinging arm or lever 26 through a pitman 35, connected at its rear end in a well-known manner to a slide adjustable in a groove in the arm or lever 26, said pitman being jointed at its forward end to the arm 36 of a three - armed rocker movable independently of the said cam - wheel 34 and having

arms 37, connected by springs 38 with clutch-dogs 39, adapted to bite on the flange of the said cam-wheel when the said rocker is moving in one direction, but being released from holding engagement with said flange when the said rocker is moving in the opposite direction, said rocker and clutch-dogs thus imparting an intermittent rotating movement to said cam-wheel. The speed of rotation of the cam-wheel 34 may be varied by adjusting the point of connection of the rear end of the pitman 35 with the swinging arm or lever 26, or the rotation of the said cam-wheel may be arrested altogether (for sewing straight seams) by bringing the connection of the said pitman to a point coincident with the fulcrum of the arm or lever 26, as will be understood. The cam-wheel 34 is provided in its rear face with a cam-groove 40, entered by a pin or roller-stud 41 on a sliding bar 42, jointed at its forward end to an arm or projection 43 on the swinging needle-bar frame or gate 19, and thus as the said cam-wheel is slowly rotated a step-by-step swinging horizontal movement across the line of the feed of the work will be imparted to the said frame or gate and to the needle-bar and needles carried thereby, so as to produce a series of stitches successively displaced from the line of the feed of the work in one direction and then a similar series of stitches in the opposite direction to produce scallops or serpentine seams, the figures of which will be varied according to the speed of rotation of the cam-wheel 34 or according to the particular form of the cam-groove in said wheel, the figures of the seam being still further varied, if desired, in either case by varying the usual work-feed. The continuously-rotating cam-wheel 23 is provided with a peripheral cam-groove 44, entered by a pin or roller-stud 45 on one arm of a bell-crank 46, having a pivotal shank or shaft 47 journaled in the bracket 48, said bell-crank being connected by a pitman 49 to an arm 50 on a rocking sleeve 51, mounted on the presser-bar 52 and having a second arm 53, to which is attached an embroidering-thread carrier 54. The said thread-carrier 54 has at its lower end an inwardly-turned finger which swings closely adjacent to and just in front of the needles 18, said finger having an eye or eyesthrough which an embroidering-thread passes in such a manner that as the said finger swings to and fro the embroidering-thread is disposed back and forth across the line of the double seam and is interwoven with and stitched down on the upper side of the work by the needle-threads, the said thread-carrier pausing at each end of its throw in either direction while the work is being fed, with the extreme end of its thread-finger slightly behind the needles, so that as the needles descend one needle or the other will come down in front of and thus lay its thread over the last lap of embroidering-thread disposed across the double seam by the said finger.

The embroidering thread or silk preferably runs from the spool 55 through a thread-guide 56, and thence through the thread-eye of a pull-off device 57, attached to the swinging arm or lever 26, thence through an intermittent tension device 58 to a constant check tension device 59, and thence to the swinging embroidering-thread carrier, by which it is guided to the work. The main shaft 14 is provided with a cam 60, which engages the inner end of the spring-pressed stem of the intermittent tension device, so as to force the spring-pressed tension-disk outward, and thus relieve the stress of the main or intermittent tension on the embroidering-thread at the moment when the said embroidering-thread is being laid across in front of the needles, the main tension on the embroidering-thread being restored before the thread-carrier quite reaches the end of its stroke in either direction, and thus the embroidering-thread is drawn taut into the stitches formed by the needles.

From the foregoing it will be understood that a great variety of ornamental figures may be made by the improved machine. Thus with the intermittently-rotating cam-wheel 34, provided with a heart-shaped cam-groove, as shown in Fig. 5, wavy or sinuous seams, such as are shown in Fig. 8, will be produced, the number of right-and-left stitches in each figure, or the size of the figures, being determined by the speed of rotation of the said cam-wheel, depending on the position of adjustment of the connection of the pitman 35 with the swinging arm or lever 26. The greater the speed of rotation of said cam-wheel the smaller the figures of the wavy or sinuous seams. With a cam-groove in the wheel 34 shaped as shown in Fig. 6 scalloped embroidering-seams, as shown in Fig. 9, will be produced, the scallops being smaller or larger, accordingly as the cam-wheel rotates faster or slower. If the point of connection of the pitman 35 be lowered, so as to be coincident with the fulcrum or center of movement of the swinging arm or lever 26, the cam-wheel 34 will remain stationary and a straight embroidery-seam, as shown in Fig. 10, will be produced, while if the embroidering-thread be omitted from the thread-carrier or the latter be removed from the machine parallel seams, which may be either straight, sinuous, or scalloped, as may be desired, (see Fig. 11,) may be produced. All of these different figures may be still further varied by varying the length of the machine-feed or by providing interchangeable cam-wheels 34, having cam-grooves of different forms from those herein shown, and thus the embroidering-figures which may be produced by the improved machine may be increased almost indefinitely.

Having thus described my invention, I claim and desire to secure by Letters Patent—

1. In a fancy stitching or embroidering machine, the combination with a stitch-forming mechanism comprising a needle-bar and two

needles, of a horizontally or laterally movable frame or gate in which said needle-bar reciprocates vertically, an intermittently-rotating cam connected with said needle-bar frame or gate and serving to impart several successive steps or movements in opposite directions, and across the line of the feed of the work, to said frame or gate and to the said needle-bar and needles, means for operating said cam, a thread-carrier, and means for moving said thread-carrier to and fro in front of said needles so as to interweave an embroidering-thread with the sewing-threads of said needles.

15 2. In a fancy stitching or embroidering machine, the combination with a stitch-forming mechanism comprising a needle-bar and two needles, of a horizontally or laterally movable frame or gate in which said needle-bar reciprocates vertically, an intermittently-rotating cam connected with said needle-bar frame or gate and serving to impart several successive steps or movements in opposite directions, and across the line of the feed of the work, to said frame or gate and to the said needle-bar and needles, adjustable means for operating said cam, so as to vary the speed of rotation, a thread-carrier, and means for moving said thread-carrier to and fro in front of said needles so as to interweave an embroidering-thread with the sewing-threads of said needles.

30 3. In a fancy stitching or embroidering machine, the combination with a stitch-forming mechanism comprising two needles and a needle-bar, of a horizontally-movable frame or part in which said needle-bar reciprocates vertically, an intermittently-rotating cam connected with said frame or part and serving

to impart a series of successive step-by-step movements alternately in opposite directions to said needle-bar frame or part, an embroidery-thread carrier movable to and fro in front of said needles across the line of the seam, a continuously-rotating cam-wheel, and connections between said cam-wheel and said intermittently-rotating cam and said thread-carrier whereby the two last-named devices are operated.

4. In a fancy stitching or embroidering machine, the combination with a stitch-forming mechanism comprising two needles and a needle-bar, of a horizontally-movable frame or part in which said needle-bar reciprocates vertically, an intermittently-rotating cam connected with said frame or part and serving to impart a series of successive step-by-step movements alternately in opposite directions to said needle-bar frame or part, an embroidery-thread carrier movable to and fro in front of said needles across the line of the seam, a continuously-rotating cam-wheel, and connections between said cam-wheel and said intermittently-rotating cam and said thread-carrier whereby the two last-named devices are operated, the connections of the said continuously-rotating cam-wheel with said intermittently-rotating cam being adjustable to permit the speed of rotation of said intermittently-rotating cam to be varied to vary the embroidery figures.

In testimony whereof I affix my signature in presence of two witnesses.

FRIEDERICK MUELLER.
